SLIDE FILING TRAY

Hiram Lawrence Mills, Prairie Village, Kans.

Application December 26, 1952, Serial No. 22,876

Term of patent 14 years

(Cl. D74—1)

To all whom it may concern:

Be it known that I, Hiram Lawrence Mills, a citizen of the United States, residing at Prairie Village, Johnson County, State of Kansas, have invented a new, original, and ornamental Design for a Slide Filing Tray, of which the following is a specification, reference being had to the accompanying drawing, forming a part hereof.

The single figure of the drawing is a perspective view of a slide filing tray showing my new design. The side opposite the one shown is substantially identical thereto; and the opposite end is plain and unornamented. The essential features of my design reside in the part shown in full lines.

I claim:

The ornamental design for a slide filing tray, substantially as shown and described.

HIRAM LAWRENCE MILLS.
